J. Goulding.

Welding Boiler Pipes.

Patented Jun. 19, 1835.

June 19, 1835

John Goulding of Boston Massachusetts
Letters Patent

The Schedule referred to in these Letters Patent and making part of the same, containing a description in the order of the said John Goulding himself of his improvement in the mode of preparing and drawing in the pipes into Boilers where the same are used for the transmission of water or heated air from one part of the boiler to another.

It all to whom these presents shall come, Whereas I John Goulding of Boston in the County of Suffolk and Commonwealth of Massachusetts, Mechanic, did on the twenty-fifth day of October in the year of our Lord one thousand Eight hundred and thirty four obtain Letters Patent of the United States for a new and useful improvement in the mode of making Boilers for generating steam and evaporating water and other fluids which improvement consisted in the arrangement and combination of two internal cylinders with connecting pipes between them all being enclosed within an outer case or cylinder as in the specification of improvement now on file in the Patent Office at Washington particular set forth. Now know ye that, the said John Goulding on the date aforesaid have discovered and applied to use a new and useful mode of preparing and drawing in the pipes into any such Boiler or into any Boiler where the same are used for the transmission of water or heated air from one part of the Boiler to another, and that the following is a full and exact description of the mode of preparing and drawing in the pipes as invented by me. In this mode annexed A represents a tube, B. b. represent two cylinders, the sides of two cases or chambers, which cylinders cases or chambers are connected by the tube A so that water or heated air may be conveyed thro' the tube from one to the other. C. is one end of the tube A upon which a ring is welded, or it is upset so as to be longer than the inside of the tube. The outer side or circumference of this long end is made tapering and varnished or bit upon the tapering.

John Goulding

part C. is the other end of the tube which is also made tapering so as to be a little smaller than the residue of the tube. A male screw is cut upon this end. The threads of these screws are all exactly equidistant. The diameter of the hole of the tube may be uniform. Apertures are made in the cylinders or sides B. They are tapering, and a female screw is cut in them so as exactly to conform in size and shape, to the size and shape of the tapering ends of the tube. The aperture in the cylinder or side B being larger than the aperture in the cylinder or side b. The tube is inserted over there. The aperture in B. which is large enough to admit its passing in until the conical end C reaches the aperture in b. when both ends are screwed home together. The length of the tapering part of the end of the tube and of the screw cut upon them will depend upon the thickness of the cylinder or the sides of the case or chamber.

I claim for my Patent, for the mode of passing and drawing my pipes into a boiler where the same are used for the transmission of water or heated air from one part of the boiler to another as above described.
